SAFETY SLING

Axel T. Nilsson, Goteborg, Sweden

Application June 6, 1942, Serial No. 446,161
In Sweden March 21, 1939

2 Claims. (Cl. 294—74)

In the use of a standard sling for supporting a load of boards or the like, the sling, after being bound around the boards and connected to a winch for lifting, pulls away from the top boards slightly and then slips along the boards a short distance during the actual lifting operation. The top boards are likely to slip out and accidents result. The principal object of my invention is to provide a safety sling for loading lumber that will grip the pile of lumber in a manner which will cause the sling to tighten about the lumber during lifting and this will prevent the sling from slipping along the pile.

A further object of my invention is to provide a device of the type described which is extremely simple in construction and durable and efficient for the purpose intended.

Other objects and advantages will appear in the following specification, and the novel features of the device will be particularly pointed out in the appended claims.

My invention is illustrated in the accompanying drawing forming a part of this application, in which:

Figure 1 is a perspective view of a pile of lumber showing my safety sling applied thereto;

Figure 2 is a detail view of the safety sling;

Figure 3 is a side elevation of the hook used in the sling; and

Figure 4 is a front elevation of the hook.

While I have shown only the preferred form of my invention, it should be understood that various changes or modifications may be made within the scope of the appended claims without departing from the spirit of the invention.

In carrying out my invention I provide a safety sling that has two hooks A of novel construction. The hooks are identical and one of the hooks is shown in detail in Figures 3 and 4. The hook A is relatively wide and has an open hook-shaped portion 1 and a closed looped portion or eye 2. The inner surface of the hook portion 1 is rounded as at 3 and the inner surface of the looped portion 2 is rounded as at 4. The back 5 of the hook is made flat so as to bear against the pile of lumber indicated generally at B in Figure 1. It is not necessary that the back of each hook contact with the pile of lumber and I have purposely shown the two hooks in Figure 2 arranged so that the back of one of the hooks contacts with the lumber pile while the back of the other does not so contact.

In forming the safety sling, an endless rope or cable C has its turned back or looped portions 6 and 7 passed through the loops or eyes 2 of the

hooks A. The two strands 8 and 9 forming the endless supporting member C are passed under the pile of lumber as indicated in Figure 1. A top cable or rope indicated generally at D has a conventional hook 10 secured at one end thereof, and then the cable is looped at 11 and receives the hook-shaped portion 1 of the hook A with a portion 12 of the cable extending over the top of the lumber B. The cable D is then looped at 13 and receives the hook-shaped portion 1 of the other hook A. The free end of the cable is now passed through the hook 10 and is extended upwardly as at 14 to be attached to the rope (not shown) that connects to the ship's winch. If desired the portion 14 may carry a hook (not shown) that is secured to an eyelet (not shown) which in turn is carried by the rope or cable that extends to the winch.

From the foregoing description of the various parts of the device, the operation thereof may be readily understood.

When the conventional sling is used, it is impossible to tighten the strands around the lumber to a point where the strands will not slip when the lumber is lifted. During the actual lifting of the load, the portion of the sling covering the top of the lumber is pulled free of the lumber top a slight distance and this permits the top boards to become loose and to slide out of the sling. My safety strap or sling overcomes this disadvantage because when it is tightened around a pile of lumber, the strand 12 is pulled taut across the top of the lumber and cannot slide along the lumber during the lifting operation. The reason the strand 12 cannot slide is that the vertical pull on the strand portion 14 will cause the rope D to thread through the hook 10 and the two hooks A so as to bind the strand portion 12 more tightly about the lumber. The rounded portions 3 on the hooks A permit this ready sliding movement of the cable D. The strand 12 is initially placed at the shortest distance around the load which means that the vertical extending portions of the ropes C and D will be arranged at right angles to the longitudinal axis of the lumber. The load is therefore held in a solid grip even before the load has fully left the ground. Different kinds of material may be lifted and the hooks A may be used with cables, chains or ropes. It will be seen that the upper portion D of the device can be the conventional sling except that instead of it being passed entirely around the load, it is connected to the hooks A. When it is so used, it ceases to be the conventional sling and forms a

part of my device. The other ends of the hooks A are then interconnected by the double looped member C. The device is extremely simple in construction and forms a positive yet simple means for lifting lumber and other material without any chance of the material sliding free.

I claim:

1. A safety sling comprising an endless strap having two looped portions, hooks engaging in the looped portions, a second strand having an automatically adjustable part with looped portions slidably engaging with the hooks, said endless strap and automatically adjustable part cooperating with each other to form the safety sling, and said second strand having a portion adapted to be connected to a load lifting means for causing the sling to tighten about the load, the second strand being entirely removable from

the strap hooks when loading or unloading the sling.

2. A safety sling comprising an endless strap having two looped portions, hooks connected to the strap at the looped portions, said strap adapted to underlie a pile of lumber or the like with the hooks arranged along the sides of the pile, and a separate load supporting strand having a portion formed into an adjustable strap that overlies the top of the lumber pile and has looped ends slidably connected to said hooks, said strand when supporting the load automatically tightening the adjustable strand and the endless strap about the pile to an extent which will prevent lumber from slipping from the pile, the strand being entirely removable from the strap hooks when loading or unloading the sling.
